COMPRESSOR CONTROLS

Norman J. Janisse, Grafton, Wis., assignor to Johnson Service Company, Milwaukee, Wis., a corporation of Wisconsin

Filed Nov. 12, 1958, Ser. No. 773,248

3 Claims. (Cl. 62—209)

This invention relates to means for controlling the operation of a compressor in a refrigeration circuit of the compressor-condenser-evaporator-type. Particularly, it relates to an automatic control means arranged to vary the adjustment of means for varying the rate of flow through the compressor, e.g., a throttling means in the suction connection of the compressor.

The purpose of the control system according to the present invention is to provide a control in which the throttling means is normally controlled by a relay responsive to evaporator temperature but in which the control is transferred from the normally controlling relay to control by a second relay when the current drawn by the compressor motor is excessive, but only when this transfer would cause a reduction in flow rate. It is well known to those skilled in the art that, under various conditions encountered in the normal operation of a refrigeration system, the density of the gases entering the compressor rises, thereby materially increasing the load on the compressor. This increased load is particularly apparent when the refrigeration system is put into operation after it has stood idle for any extended period of time. Under conditions of overload, the compressor motor will draw an excessive current. Unless a motor large enough to operate under any normally encountered overload load is used, it is necessary to provide means to limit the current drawn by the motor. This current limitation may be performed and usually is performed by some type of automatic means effective to vary the load on the compressor. This load-varying means may take a variety of forms. It may be, as has been suggested above, a throttling valve to vary the rate of flow through the compressor. If a reciprocating piston-type of compressor is being used, the control system may be actuated so as to remove the load from one or more of the pistons or to increase the clearance space in the compressor cylinders, or it may be a control which will hold either the suction or the exhaust valves of the compressor open. All of these forms of control are well known in the art, and the present invention is useful regardless of the type of flow-rate-varying control which is used in the compressor.

According to the present invention the throttling means, in the compressor suction connection, is provided with a fluid pressure-operated actuator which is operable to shift the throttling means through its adjusting range. This fluid pressure actuator is selectively controlled by either of two fluid pressure-actuated relays. These relays may be of either the Class I type or of the Class II type; the terms Class I and Class II being in every day use in the industry and designating, respectively, a direct-acting and a reverse-acting relay. Each relay is of a different class. A selector valve mechanism is provided which has two inlets, one connected to the branch line of one of the relays and the other to the branch line of the other relay. The selector valve mechanism has a single outlet which is connected with the fluid pressure-operated actuator. The selector valve mechanism includes a motor connected to shift the selector valve between two operating posi-

tions, namely, a position in which it connects one of its inlets in flow communication with its outlet, and a second position in which it connects the other of its inlets with its outlet. The valve shifting motor includes two opposed working spaces; each working space being connected in flow communication with a different branch line. The valve shifting motor acts in response to the difference between the pressures in the respective branch lines to interconnect its outlet with that branch line whose pressure will cause the actuator to shift the throttling means to produce the lower rate of flow through the compressor.

The first relay is responsive to a temperature produced by the evaporator. The second relay is responsive to the amount by which the current drawn by the electric motor driving the compressor exceeds a predetermined value.

It is preferred that the thermostat be a Class I instrument. Since the current-responsive relay is of the other class, it will be a Class II instrument. The valve actuator will cause the throttle to close as the pressure it receives falls. In this preferred form, the selector valve will select the lower branch line pressure for transmission to the actuator. This embodiment is preferred for the reason that if either branch line is damaged or ruptured, the selector valve will connect that branch line to the actuator, causing the throttling means to assume the position in which the minimum rate of flow through the compressor is established. If the thermostatically controlled relay is a reverse-acting instrument and the current-responsive relay is a direct-acting instrument, the selector valve will select the higher branch line pressure for transmission to the actuator, and the actuator would be of the type in which rising pressure will close the throttle valve.

The presence of the selector valve mechanism means that the actuator is never connected simultaneously to the branch lines of both relays. In this way, the control function of each relay is independent of the control function of the other relay. This independent control, by different relays, results in a control system whose operation is unusually stable when contrasted to control systems in which the two relays were not selectively connected to the actuator but were connected to it simultaneously.

The invention will be described having reference to the accompanying drawings, in which:

Fig. 1 is a diagrammatic showing of a refrigerative device equipped with a control system embodying the present invention.

Fig. 2 is a similar diagrammatic showing of an alternate arrangement of the control system.

Fig. 3 is an axial section through the selector valve mechanism. As here shown, the selector valve will transmit the higher of the two pressures supplied thereto.

Fig. 4 is an axial section of the selector valve, but here shown arranged to select the lower of the supplied pressures.

Fig. 5 is a sectional view, partly in elevation, showing a piloted relay valve used in the system illustrated in Fig. 1.

Refer first to Fig. 1. As shown, the refrigeration unit comprises a compressor 11, a condenser 12 and an evaporator 13, connected together to form a conventional refrigerative circuit. Compressor 11 is connected to be driven by an electric motor 14. The rate of refrigerant flow through the compressor 11 is controlled by a throttle valve, indicated in this figure as consisting of a simple butterfly valve 15, located in the suction connection of the compressor 11. The valve is positioned by a fluid pressure actuator 16. This actuator 16 receives fluid pressure from a selector valve mechanism 17, which selectively connects the actuator 16 with an overload relay 18 or with a thermostatically piloted relay valve 19.

The thermostat is shown at 21 and, as shown, is responsive to the temperature of evaporator 13.

The relays 18 and 19 and the thermostat 21 each receive air under pressure from an air supply, identified by a legend on the drawing. Relay 18 has its branch line 22 connected to an inlet of the selector valve 17. Similarly, the branch line 23 of relay 19 is connected to the other inlet of the selector valve 17. The thermostat's branch line 24 is connected with relay 19 to pilot its operation. The overload relay 18 and thermostat 21 are familiar commercially available fluid pressure relay valves whose construction is well known in the control art. While the selector valve 17 and the piloted relay 19 are also commercially available, their construction is not so well known. Since knowledge of the operation of these relays is essential to understanding the present invention, two different embodiments of the selector valve 17 are shown in Figs. 3 and 4, and the piloted relay 19 is shown in Fig. 5.

Referring to Fig. 3, the selector valve 17 includes a housing 25 and a cover plate 26, secured together by bolts (not shown). Confined between the body 25 and cover plate 26 is a reversible valve assembly 27. As shown, this valve assembly comprises three spaced, annular diaphragms clamped at their peripheries between the body 25, two annular spacers and cover plate 26. The peripheries of the central openings in the diaphragms are clamped between a flange on the tubular valve member 28, small annular spacers and a nut. The body includes inlet passages 29 and 31 which communicate, respectively, with diaphragm chambers 32 and 33. The body 25 has an outlet connection 34 which communicates directly with outlet chamber 35 which is, in turn, in constant open communication with outlet chamber 35'. Chambers 35 and 35' communicate with one another by way of radial ports in the tubular valve member 28 and the notches adjacent its opposite end. Cone valves 36 and 37, which are spring-biased toward closed position, control flow from inlet passages 29 and 31, respectively, to the communicating outlet chambers 35 and 35'. It will readily be apparent that a dominant pressure in inlet 31 will shift the valve member 28 in a direction to open cone valve 36 and interconnect inlet 31 with the outlet 34. A dominant pressure in inlet connection 29 will unseat valve 37 whereby pressure is admitted to outlet 34 from the inlet 29.

The selector valve shown in Fig. 4 is the same as that shown in Fig. 3 except that the valve assembly 27 has been reversed. With this assembly of the parts, a dominant pressure in the inlet 31 will cause cone valve 37 to be unseated thereby admitting pressure to the outlet 34 from the inlet connection 29. A dominant pressure in inlet connection 29 similarly will connect inlet 31 with the outlet 34. Thus it will be seen that the Fig. 3 arrangement selects the higher inlet pressure for transmission to the outlet, while the Fig. 4 arrangement causes the lower inlet pressure to be transmitted to the outlet. As has been pointed out, these selector valve mechanisms are commercially available. More complete details concerning their construction may be had from applicant's assignee and by reference to that assignee's Apparatus Bulletin C 120.

The piloted relay 19 shown in Fig. 5 is also a commercially available device and is fully described in applicant's assignee's Instruction Buletin D 265 A. As shown in Fig. 5, the relay includes a housing having a supply connection 38, an outlet or branch line connection 39, and a pilot pressure connection 41. The housing has three diaphragm chambers 42, 43 and 44 therein. Chambers 42 and 43 are in constant open communication with each other and with the outlet connection 39. A supply and exhaust valve assembly 45 controls the admission of fluid to and the exhaust of fluid from chambers 42 and 43. Fluid is admitted through the supply valve from the connection 38 and is vented through exhaust

port 46. The supply and exhaust valve 45 is shown in lap position with both the supply and exhaust valves closed. Upward movement of the diaphragm leaves the supply valve closed and opens the exhaust valve. Downward movement of the diaphragm reverses this valving. The diaphragms in chambers 42 and 43 are of equal area. A lever 48 is pivoted to diaphragm retainer 49 at 51. The pivot joint 51 is located midway between diaphragm follower screws 52 and 53 which engage the diaphragms of chambers 42 and 43, respectively. Lever 48 carries a third diaphragm follower screw 54 which engages the diaphragm of pilot chamber 44. An adjusting spring 50 engages the lever 48, as shown.

Because of the equal areas of the diaphragms in chambers 42 and 43 and the location of pivot 51, the position of lever 48 is indifferent to the pressure which exists in the outlet connection 39. Thus, it will be apparent that as pressure in the pilot chamber 44 increases, the left-hand end of lever 48 will move downward, causing the supply valve to open and admit pressure fluid from the supply connection 38 into the chambers 42 and 43. This pressure fluid, in turn, flows to the outlet connection 39.

As shown in Fig. 1, the outlet connection 39 of the piloted relay 19 is connected to branch line 23 and thereby to the inlet of the selector valve 17 whose outlet, in turn, is connected to supply pressure fluid to the damper motor 16. Movement of the damper motor 16, in response to variations of the pressure in its supply connection, will vary the tension of spring 55. This spring 55 is connected between the movable element of the motor 16 and the arm 56. Referring again to Fig. 5, it will be seen that the arm 56 is rigidly connected to the lever 48 and increasing spring tension causes the arm 56 to act in opposition to the pressure in chamber 44, thereby causing the lever 48 to return to its balanced position in which the supply and exhaust valves are lapped. A reduction of pressure in the chamber 44 will cause the lever 48 to open the exhaust valve, thereby venting pressure fluid from the outlet connection 39 which will have the effect of reducing the tension in the spring 55 whereby the lever 48 is restored to its balanced position to again lap the supply and exhaust valves. From this, it will be apparent that the pressure present in the outlet connection 39 will vary in accordance with variations of the pressure in the chamber 44. The pilot connection 41 is shown connected with the branch line 24 of the thermostat 21 in Fig. 1. The outlet connection 39 is connected with the branch line 23, while the supply connection 38 is connected to the air supply, as shown.

Refer again to Fig. 1. Relay 18 is a pneumatic relay of the type shown on the Otto Patent 1,500,260 assigned to applicant's assignee. The lid which controls the bleed port is connected to be shifted progressively by a solenoid which is energized by the current flow through the secondary circuit of a transformer 57 whose primary winding is connected in series with the compressor motor 14. The pressure in the branch line 22 of this relay remains constant so long as motor current is below a prescribed amount. When this current is exceeded, the relay 18, if direct-acting, will increase its branch line pressure. If it is reverse-acting, as it will be in the illustrated preferred embodiment, the branch line pressure will be reduced.

In a typical installation, the supply pressure would be on the order of 20 pounds per square inch. The branch line pressure from the relay 18 would vary between 13 p.s.i. and 8 p.s.i. The pressure in the branch line 24 of thermostat 21 would vary between an upper limit of 15 p.s.i. and a lower limit of 5 p.s.i. The pilot relay 19, under the control of the pressure in branch line 24, might vary between 8 and 13 p.s.i. The fluid pressure actuator 16 would be designed to be moved between its extreme positions by pressures in the 8 to 13 p.s.i. range.

In the normal operation of the system, overload cur-

rents would be encountered only under conditions of abnormally high cooling loads. When abnormally high cooling loads are encountered, the thermostat 21 will increase its branch line pressure, causing pilot relay 19 to increase its branch line pressure and cause the valve 15 to assume its maximum flow position. If the thermostat 21 is direct-acting, the pressure in branch line 23 would be 13 p.s.i. This pressure, formerly the lower one received by selector valve 17, is still not greater than the 13 p.s.i. normally present in branch line 22, and the selector valve will transmit this pressure. This abnormally high cooling load is likely to cause an excessive current to be drawn by the motor. This excessive current will cause a reduction of pressure in branch line 22, thus immediately causing the selector valve 17 to shift over and transmit this pressure to the actuator 16. A reduction of pressure in actuator 16 will permit valve 15 to move toward closed position. This will, in turn, reduce the tension in spring 55 whereby the supply valve of the relay 19 will open because the pressure in diaphragm chamber 44 will not have changed. This will charge the branch line 23 with air at 20 p.s.i. In this way, the selector valve is prevented from shifting back until the pressure in the thermostat's branch line is reduced, which is an indication that the system has restored a proper temperature at the evaporator and need not continue to operate at full capacity.

When the overload relay restores its branch line pressure to full value, the valve 15 will again be in maximum open position, restoring the tension of spring 55 and causing the pilot relay 19 to lap. Any reduction of the pressure in the thermostat's branch line will vent pressure from the branch line of relay 19. When this pressure falls below the pressure in branch line 22, the selector valve 17 will resume normal position and the relay 19 will again be in control to establish the proper setting of valve 15.

The advantage of this system is that once the overload relay 18 responds to an overload current, it remains in command until the refrigeration apparatus can meet the cooling demand without producing an overload current. Thus the system operates at maximum safe capacity to overcome the abnormal cooling load.

In some installations the stability, afforded by locating the piloted relay 19 in the position shown in Fig. 1, can be sacrificed in order to permit use of the control system to control the operation of more than one actuator, such as 16. This alternate form of control system is shown in Fig. 2. The reference numerals applied to the components of this system are the same as the reference numerals applied to the same components in the Fig. 1 system, except that they are followed by the designation prime.

As shown in Fig. 2, the refrigeration system comprises a compressor 11', a condenser 12', an evaporator 13', a throttling valve 15', and a fluid pressure actuator 16' connected to vary the position of the valve 15'. The compressor is driven by an electric motor 14'. The control system comprises an air supply (indicated by legend), an overload relay 18', a selector valve 17', a thermostat 21', and a piloted relay 19'.

As shown, the air supply is connected to supply air to the thermostatic relay 21' and the overload relay 18'. The branch lines 24' and 22' are connected to the inlets of the selector valve 17'. The outlet 58 of the selector valve is connected to supply air to the pilot connection of the relay 19'. The supply connection 38' of the relay 19' receives air from the air supply and, in accordance with the variation of pressure in the outlet 58, pilots the admission of air to the fluid pressure actuator 16' through the branch line 23'. The outlet connection 58 has a second branch 59, as shown, which may be connected to the piloted relay of other fluid actuators whose operation are to be controlled. This arrangement is resorted to because the flow capacity

of the thermostats 21 and 21' is small compared to that of the relays 19 and 19' and it is desirable, in order to assure quick response of the controlled actuator, to provide a piloted relay which is directly associated with each fluid pressure actuator.

While the embodiment shown in Fig. 2 is not quite as stable under overload conditions as is the Fig. 1 embodiment, its operation is satisfactory. It should be particularly noted that in each embodiment the actuator 16 or 16' is selectively and independently controlled by the corresponding thermostat or overload relay, depending on the current drawn by the motor.

What is claimed is:

1. In a compressor-condenser-evaporator refrigerative circuit unit of the type including an electric motor to drive the compressor and throttling means adjustable to vary the rate of refrigerant flow through the compressor, the combination of control means to adjust the throttling means comprising in combination a fluid pressure-operated actuator connected with the throttling means to adjust it; a selector valve mechanism having two inlet connections and an outlet connection, said outlet connection connected to the actuator; a first fluid pressure-operated relay responsive to a temperature produced by the evaporator and having its branch line connected to supply fluid to one of the inlets of the selector valve mechanism; a second fluid pressure-operated relay responsive to the amount by which the current drawn by the electric motor exceeds a predetermined value, the second relay being of a class different from the class of said first relay and having its branch line connected to supply fluid to the other inlet of the selector valve mechanism; fluid pressure motor means to shift the selector valve mechanism and having two opposed working spaces, each space being in constant free flow communication with a different one of said branch lines, the motor means serving in response to a difference between the branch line pressure to interconnect the outlet with that inlet which will cause the actuator to adjust the throttling means to produce the lower rate of refrigerant flow.

2. The combination defined in claim 1 in which said first fluid pressure-operated relay is a direct-acting relay.

3. In a compressor-condenser-evaporator refrigerative circuit unit of the type including an electric motor connected to drive the compressor and means adjustable to vary the rate of refrigerant flow through the compressor, the combination of control means to adjust the flow-rate-varying means comprising in combination a fluid pressure-operated actuator connected with the flow-rate-varying means to adjust it; a selector valve mechanism having two inlet connections and an outlet connection, said outlet connection connected in flow communication with the actuator; a first direct-acting fluid pressure-operated relay having a supply connection, an exhaust connection and a branch line and including a supply and exhaust valve, a valve operator, a pressure motor connected to said operator and urging said valve toward supply position, and spring means connected between the movable element of said actuator and the operator and urging said supply and exhaust valve toward exhaust position, said relay having its branch line connected to one inlet of said selector valve; a direct-acting fluid pressure-operated thermostatic relay, responsive to evaporator temperature and having a branch line connected to supply fluid to said pressure motor; a reverse-acting fluid pressure-operated relay responsive to the amount by which the current drawn by the electric motor exceeds a predetermined value and having a branch line connected to supply fluid to the other inlet of the selector valve mechanism; fluid pressure motor means to shift said selector valve mechanism and having two opposed working spaces, one space being in constant free flow communication with the branch line of said reverse-acting relay, and the other being in constant flow communication with the branch

line of said first relay whereby the pressure differential between branch lines controls, the connection of the branch lines being so chosen that the selector valve mechanism transmits the lower branch line pressure to its outlet.
